UNITED STATES PATENT OFFICE

2,204,991

AUTOMOBILE HOOD

Jules Haltenberger, Ann Arbor, Mich.

Application January 26, 1940, Serial No. 315,821

4 Claims. (Cl. 180—69)

My invention relates to automobile hood constructions, and this application is a continuation-in-part of my co-pending application for "Automobile hood," Serial No. 204,717, filed April 5 28, 1938, now Patent 2,188,891.

It has been proposed with centrally hinged hoods, to terminate them adjacent the front doors. It is here proposed to hinge a hood substantially at its extreme sides, while maintaining an exposed ventilator shelf, and in the preferred form, hinge it directly on the body of the automobile, and terminate the hood directly at the front edges of the front doors, both for a lengthening effect, and for the elimination of matched 15 surfaces.

A further object is to provide, adjacent to front doors, automatic vertical adjustments for the hood rear corners.

Further objects of my invention will appear 20 as the description proceeds.

The accompanying drawing illustrates my invention. Here, Fig. 1 is a side elevation of the fore part of an automobile; Fig. 2 is a plan view of a part of the automobile illustrated in Fig. 1, here, with some parts left off; Fig. 3 is a section substantially on lines 3—3 of Fig. 1, here, with some parts left off; Fig. 4 is a section substantially on lines 4—4 of Fig. 1, here illustrated in a larger scale; Fig. 5 is a section substantially on 30 lines 5—5 of Fig. 4; Fig. 6 is a modification of the invention.

Referring to Figs. 1 to 5 inclusive, it will be seen that an automobile body generally at 10 is provided with a roof 11, windshields 12, and exposed ventilator shelf 13 carrying a usual ventilator 14. This shelf is formed into a hood ledge 15, and terminates in a usual dash board 16.

On the body are mounted a pair of front doors, having main panels 17, body beads 18, curved walls 20, upper frames 21, and windows 22. Directly in front of panels 17, door gaps 23 are provided (only one is shown). These are formed by the rear edges of the hood panels 24. Panels 17 and 24 are in surface alignment. In the preferred form, panels 24 are formed into front fenders 25 (only one is shown).

The fore part of the body is formed into a usual cowl structure, having fully spaced side walls 26 and closer spaced side walls 27. On hood ledge 15, where it laterally terminates in walls 26, an anti-squeak (preferably rubber) hood supporting liner 28 is provided.

The body cowl structure supports a hinged hood carrying bridge 30 as by spot welded brackets 31, and single hinge pins 32, indicated in Figs.

1 and 2. As is clear from Figs. 4 and 5, pins 32 are provided with washers 33 and lock nuts 34. Pins 32 operate in vertically elongated openings 35 in door pillar side walls 36.

Bridge 30 serves as an adapter for an alligator hood generally at 40, having a substantially horizontal upper wall 41 (in surface alignment with shelf 13), depending walls 42 (in surface alignment with walls 20), beads 43, and in-turned horizontal under walls 44. In the bridge 30, elongated bolt holes 45 and therein mounted bolts 46 form a longitudinal adjustment and securing means between the bridge and hood under walls, assuring a desired direct spacing gap between the hood shelf and door curved walls. 15

By these single hinge pins the hood is operable for opening and closing. At the rear of liner 28, pins 32 automatically adjust themselves in the vertically elongated openings, maintaining the hood in the desired longitudinal relation to the body to assure constant direct door gaps 23 and a corresponding hood to ventilator shelf gap 41. 20

For locking the hood in closed position, a well known structure (not new with the applicant) is schematically indicated in Fig. 1; here, a pilot 25 and catch pin 50, a fulcrumed trigger 51 (catch spring not shown), driving compartment operated release rod 52, and initial hood opening spring 53 compose the main elements. This construction is used on many cars; it is simple and 30 prevents the theft of the battery (now usually in the engine chamber). This is a single point locking and releasing, and a simple "slam closing" hood lock system.

It is desired to depress the hood rear end when 35 in locked position to prevent rattles. As is clear from Figs. 1, 2 and 3, bridge 30 is provided with a roller 54, riding on the surface of a cam-shaped spring 55, secured to dash board 16, as by bolts 56. In the position illustrated, the lateral angle 40 portion of the spring will hold the hood downwardly by the component of about 45° angle. When the hood is manually lifted and the roller passes the hump 55', the spring will assist in lifting the hood. When the roller reaches the upper 45 curved nest 55'', the hood will be held in open position, by the exerted spring pressure on the cam corner (at the base of nest 55'').

The above described alligator hood system is simple; it eliminates matched surfaces, it has 50 only two self-aligning fulcrum pins and one remote controlled lock pin.

Figs. 1 to 5 inclusive illustrate a single hinged alligator hood construction in direct spacing from the doors and hood shelf. Directly spaced 55

- alligator hood construction is not limited to a single hinged system, when it is desired to use a directly spaced hood arranged to be supported by a differential hinge. This is illustrated in Fig. 6.
- 5 Differential hinges are not new with the applicant, and as is clear from the drawing, here adjustable brackets 60 (only one is shown) are secured to the depressed cowl side walls 27. On these brackets are fulcrumed the differential 10 links 61 and 62. The upper ends of these links are connected to hood brackets 63 (only one is shown). These brackets are attached to the alligator hood in the usual manner, and as customary, they are interconnected by a bridge 64. Coil 15 springs 65, by their toggle position, depress the hood rear end. When the hood is in open position, by reaching the opposing toggle position (not shown) the springs will hold the hood in open position.
- 20 Alligator hood construction is gaining, and the elimination of matched surfaces reduces the cost of construction and increases the lengthening effect even when exposed door pillars are provided below the hood, (not shown). For certain 25 applications, I may continue the hood depending side walls below the usual bead line (not shown).

What applicant claims as his invention:

1. In an automobile, a body forwardly terminating in a cowl structure, front doors on said 30 body having outer surfaces and front edges, a

windshield on said cowl structure, an exposed ventilator shelf formed at the top of said cowl structure in continuation of said windshield and a ventilator therein, a hood ledge in longitudinal and lateral continuation of said shelf, an alligator hood on said ledge aligned with said shelf and having lateral portions terminating at said door edges in surface alignment with said door surfaces, and hinge means for said hood at substantially the extreme sides of said cowl structure. 5

2. The invention described in claim 1, wherein 10 spring means depress said hood in closed position and support said hood in open position.

3. In an automobile, a body forwardly terminating in a cowl structure, front doors on said 15 body having outer surfaces and front edges, a windshield on said cowl structure, an exposed shelf formed at the top of said cowl structure in continuation of said windshield, a hood ledge in longitudinal and lateral continuation of said 20 shelf, an alligator hood on said ledge aligned with said shelf and having lateral portions terminating at said door edges in surface alignment with said door surfaces, and hinge means for said hood at substantially the extreme sides of 25 said cowl structure.

4. The invention described in claim 3, wherein 20 spring means depress said hood in closed position and support said hood in open position.
